DESIGN FOR A TOILET ACCESSORY JAR OR SIMILAR CONTAINER

Charles H. Oestreich, Brooklyn, N. Y.

Application October 9, 1935, Serial No. 58,898

Term of patent 3½ years

To all whom it may concern:

Be it known that I, Charles H. Oestreich, a citizen of the United States of America, residing in Brooklyn, county of Kings, city and State of New York, have invented a new, original, and ornamental Design for a Toilet Accessory Jar or Similar Container, of which the following is a specification, reference being had to the accompanying drawing, forming a part thereof.

Figure 1 is a top plan view of the toilet accessory jar or similar container showing my new design, only a portion of the ornamentation being shown complete, it being understood that the remaining

portion involves a mere repetition of the part more fully illustrated.

Figure 2 is a front view thereof, only a portion of the ornamentation being shown complete, it being understood that the remaining portion involves a mere repetition of the part more fully illustrated.

Figure 3 is a side view of the cover handle of Figure 1.

I claim:

The ornamental design for a toilet accessory jar or similar container as shown and described.

CHARLES H. OESTREICH.
